UNITED STATES PATENT OFFICE.

ZAY JEFFRIES, OF EAST CLEVELAND, OHIO, ASSIGNOR TO THE ALUMINUM CASTINGS COMPANY, OF CLEVELAND, OHIO, A CORPORATION OF OHIO.

INTERNAL-COMBUSTION MOTOR.

1,347,480.

Specification of Letters Patent.

Patented July 20, 1920.

Application filed October 23, 1916, Serial No. 127,153. Renewed November 8, 1919. Serial No. 336,734.

To all whom it may concern:

Be it known that I, ZAY JEFFRIES, a citizen of the United States, residing at East Cleveland, in the county of Cuyahoga and

5 State of Ohio, have invented certain new and useful Improvements in Internal-Combustion Motors, of which the following is a specification, reference being had therein to the accompanying drawing.

10 This invention relates to an improved cylinder and piston construction for internal combustion motors.

In order to decrease the weight of such motors, it has recently been proposed to 15 make the cylinder casting and piston of metallic alloys of low specific gravity, such as alloys of aluminum. In these motors the cylinder casting has been bored out and fitted with a cylindrical liner of iron or

20 steel to take the wear of the piston. While these motors are a notable advance over earlier heavy forms of construction, they have some disadvantages which attach to the liners used. Some advantages accrue

25 from a relatively thin and uniform lining sleeve of ferrous metals, as compared with a unitary cylinder lining of iron; nevertheless, because of the marked difference in the coefficients of thermal expansion of the me-

30 tallic alloy of the piston and the ferrous metal of the liner, it has been necessary to provide a comparatively large clearance between the piston and the liner to avoid seizing when the motor heats up in opera-

35 tion.

This large clearance causes piston slap and oil pumping when the motor is starting and for that reason is highly objectionable. Furthermore, by reason of the fact that the

40 thermal conductivity of the alloy metals of the piston and of the cylinder casting are materially higher than that of the iron or steel liner, the distribution of the heat in the liner is not as uniform as it otherwise

45 would be and unequal expansion and distortion, and consequently undue friction between the piston and the liner, results. Also by reason of the high thermal conductivity of the alloy metals employed, these motors

50 have tended to run at a temperature too low to secure the highest possible thermodynamic efficiency.

The main object of the present invention is to overcome the foregoing difficulties and 55 this is accomplished by providing a motor

with an aluminum alloy piston working in a composite cylinder comprising a cylinder casting of aluminum alloy bored out to receive a cylindrical liner of specially treated aluminum alloy adapted to withstand 60 the wear of the piston, this liner having a coefficient of thermal expansion approximately the same as that of the piston and being constructed and arranged in the cylinder casting so as to permit an expansion 65 of the liner corresponding to that of the piston so that the latter can be fitted with a small clearance.

A further object of the invention is the provision of a construction such as last referred to having the cylinder casting and the liner constructed and arranged to permit of the expansion of the liner in relation to the cylinder casting in a manner to control the working temperature of the mo- 75

70 tor.

In order that the invention and the manner of carrying it out may be clearly understood, I will now describe one form of construction embodying the invention. 80

In the drawing—

Figure 1 is a transverse vertical section of one of the cylinders of an engine embodying my improvements.

Fig. 2 is a side elevation of a cylinder 85 liner.

Fig. 3 is a fragmentary sectional view on an enlarged scale showing the cylinder construction.

Referring in detail to the construction 90 illustrated, 1 designates the cylinder casting in its entirety, said casting being made of aluminum alloy suitable for the purpose and comprising the cylinder wall 1^a, the water jacket 1^b, suitable intake and exhaust valve 95 1^c, and the upper crank case section 1^d.

The cylinder casting has its main cylindrical chamber bored out to receive a tubular liner 2. With the object of producing a 100 cylinder lining member having a coefficient of thermal expansion approximating that of the aluminum alloy piston to be used and having bearing qualities suited to withstand the wear of the piston, I make the liner 2 105 of aluminum alloy of suitable composition for this purpose and form the liner by casting the alloy in a permanent metal mold, and preferably the casting is made by the gravity method. In a liner thus produced 110

the metal is dense and solid throughout and near the surface is characterized by a peculiar density and hardness resulting from the action of the metallic walls of the mold.

5 Consequently the liner thus produced machines well, it being understood that the softer aluminum alloys are very deficient in this respect, and, in addition, the hard dense texture of the superficial parts of the metal 10 gives the liner excellent wear-resisting qualities.

The liner 2 has its inner surface accurately bored out to receive the piston. At its upper end the liner is formed with an 15 out-turned flange 2^a which fits in a corresponding countersink in the upper end of the cylinder casting, and serves to center the liner in the cylinder bore. At its lower 20 end the liner is similarly centered by an external enlargement or collar 2^b which fits the bore of the cylinder casting.

Between the flange 2^a and the collar 2^b the exterior of the liner is finished with an outside diameter less than the diameter of 25 the bore of the cylinder casting so that when the motor is cold this outer wall of the liner is out of contact with the surrounding wall of the cylinder casting, this clearance being provided to permit the expansion of the 30 liner when the motor warms up. I prefer to make this clearance such that when the parts reach the working temperature, the outer wall of the liner has expanded to bring more or less of its surface into close 35 contact with the surrounding wall of the cylinder casting.

If desired, the adjacent walls of the cylinder casting and liner may be given plain cylindrical finish so that when the expansion 40 of the liner occurs its surface is brought into contact with the surrounding cylinder wall throughout its entire area. I prefer, however, to form the adjacent walls so that only a part of the exterior surface of the 45 liner is brought into close contact with the cylinder wall when the expansion occurs, and the transfer of heat to the water jacket is correspondingly checked and the motor kept at a suitable working temperature. To this 50 end, in the construction shown, I have depressed or cut away a part of the outer surface of the upper part of the liner lying adjacent the water jacket and have correspondingly depressed or cut away the entire 55 outer surface of that part of the liner extending from the water jacket down to the collar 2^b. This formation of the outer wall of the liner may readily be accomplished by machining and preferably I form the depression in the upper part of the sleeve by 60 machining a continuous spiral groove 2^c thus forming a square spiral thread 2^d, the outer surface of which comes into contact with the cylinder wall when the liner expands. The amount of clearance provided 65

between the square thread and the surrounding cylinder wall will depend upon the size of the cylinder and various other factors.

The upper end of the cylinder is closed by 70 a head casting designated as an entirety by 3, this casting having a water jacket 3^a communicating in the usual manner with the water jacket 1^b of the cylinder casting. The combustion space 4 formed in the head casting has an extension 4^a which communicates with the inlet and exhaust passages through valve controlled openings in the usual manner; in the drawing the exhaust valve is shown at 5 and it will be understood that 80 the inlet valve is in that part of the structure which does not appear.

The sleeve or liner 2 may be secured in the cylinder in any desired manner but is preferably clamped in place by the head casting 3 85 which, of course, is securely attached to the cylinder casting 1.

6 designates a piston arranged to reciprocate in the cylinder liner in the usual manner, being connected by a pitman 7 with the 90 crank 8 of the engine shaft 9. This piston is made of aluminum alloy of suitable composition. The piston is provided with packing rings 10 of any preferred form and construction, and, in other respects, the piston 95 may be of any suitable form and construction.

Heretofore in motors with aluminum pistons a relatively large clearance has been provided for the piston, but in my improved 100 motor, since the coefficients of thermal expansion of the piston and cylinder materials are approximately the same, the piston is fitted to the bore of the liner substantially or nearly as closely as a cast iron piston 105 would be fitted to the bore of a cast iron cylinder.

In the operation of my improved motor, the cylinder liner when cold is entirely out of contact with the surrounding cylinder 110 wall except at the flange 2^a and the collar 2^b; but, as the piston and liner absorb heat from the combustion gases, they both expand until the working temperature is reached, at which point, or slightly before it, the 115 outer surfaces of the projecting thread 2^d are brought into close contact with the cylinder wall. Until this latter contact is established, the liner is thermally insulated from the surrounding cylinder wall by the interposed envelop of air and consequently the cylinder and piston rise quickly to working temperature and the motor is correspondingly easy to start. As soon as contact between the liner and the surrounding cylinder 120 wall is established, excess heat begins to be conducted to the water jacket and the parts are thus kept at a suitable working temperature.

A composite cylinder, properly designed 130

and constructed in accordance with my invention, has a peculiar automatic governing action on the working temperature of the engine; for if the temperature falls to a certain value the resultant contraction of the cylinder parts causes the external surface of the liner to draw away from the wall of the cylinder casting so that the conduction of heat to the latter is at once checked and the working temperature of the motor tends to build up again. This action, as stated, is automatic in its nature.

Furthermore, where aluminum alloys are used as the constituent material of the main cylinder wall or casting as well as of the liner and piston, the relatively high thermal conductivity of all these parts results in a cooling action that is both effective and uniform over the different parts of the cylinder and causes a uniform expansion and contraction of the parts, and especially of the liner.

As has been stated, the piston, when the parts are cold, has only the minimum clearance necessary for smooth operation; and, inasmuch as both piston and cylinder liner expand together when the motor heats up, no seizing of the piston occurs but, on the contrary, the small initial clearance is maintained substantially constant. I therefore entirely avoid the objectionable piston slap and oil pumping which has characterized prior motors with iron liners and aluminum pistons.

As I have already indicated, the clearance provided between the outside diameter of the liner and surrounding cylinder wall will depend upon the form and dimensions of the motor and is preferably to be determined in each case experimentally, as is also the area of contact between the liner and cylinder wall. My experience indicates that in most cases the clearance in question will run between four and ten thousandths of an inch for cylinders running from three to four inches in diameter.

In the modified form of my invention, set forth in my copending application Serial No. 127,152, filed October 23, 1916, the main cylinder wall is formed of iron. I prefer, however, a construction such as is herein set forth both because it results in a reduction in the weight of the engine, in comparison with said other form of construction, and also because of the highly effective and uniform cooling, above referred to, which can not be attained with an iron cylinder wall because of its lower thermal conductivity and consequent slower action in conveying heat away from the different parts of the liner.

I have elected to claim in my copending application, above identified, the patentable subject matter common to it and the present application.

Those skilled in the art will understand that various changes in the form and pro-

portions of the parts may be made in carrying out my invention. The construction herein set forth is for purposes of illustration and explanation and in no sense intended as a limitation of my invention.

What I claim is:

1. In an internal combustion motor, the combination with a composite cylinder comprising an aluminum alloy casting with a cylindrical wall surrounded by cooling means, and a cylindrical liner secured concentrically within the said cylindrical wall, the said liner being made of a metallic alloy having a high coefficient of thermal expansion approximating that of the alloy of the said casting and having its outside diameter less than the diameter of the inner wall of the casting to afford a clearance between the liner and casting adapted to be taken up by the expansion of the liner when heated by the internal combustion within the motor, of an aluminum alloy piston arranged to reciprocate in the liner.

2. In an internal combustion motor, the combination with a composite cylinder comprising an aluminum alloy casting with a cylindrical wall surrounded by cooling means, and a cylindrical liner secured concentrically within the said cylindrical wall, the said liner being made of a metallic alloy having a high coefficient of thermal expansion approximating that of the alloy of the said casting and having its outside diameter less than the diameter of the inner wall of the casting to afford a clearance between the liner and casting adapted to be taken up by the expansion of the liner when heated by the internal combustion within the motor, and part of one of the adjacent surfaces of the cylinder wall and liner being recessed to form heat insulating space between said adjacent surfaces, of an aluminum alloy piston arranged to reciprocate in the liner.

3. In an internal combustion motor, the combination with a composite cylinder comprising an aluminum alloy casting with a cylindrical wall surrounded by cooling means, and a metal mold cast cylindrical liner of aluminum alloy secured concentrically within the aforesaid cylindrical wall, the liner having its outside diameter less than the diameter of the adjacent inner wall of the casting to afford a clearance between the liner and casting adapted to be taken up by the expansion of the liner when heated by the internal combustion within the motor, of an aluminum alloy piston arranged to reciprocate in the liner.

4. In an internal combustion motor, the combination with a composite cylinder comprising a casting with a cylindrical wall surrounded by cooling means, and a cylindrical liner secured concentrically within the said cylindrical wall, the liner having its outside diameter less than the diameter of the inner

- wall of the casting to afford a clearance between the liner and casting adapted to be taken up by the expansion of the liner when heated by the internal combustion within the motor, of a piston arranged to reciprocate in the liner, the said casting, liner and piston being made of metals having approximately the same coefficients of thermal expansion.
10. 5. In an internal combustion motor, the combination with a composite cylinder comprising a light weight metallic alloy casting with a cylindrical wall surrounded by cooling means, and a cylindrical liner secured 15 concentrically within said cylindrical wall, the liner having its outside diameter less than the diameter of the inner wall of the casting to afford a clearance between the liner and casting adapted to be taken up by 20 the expansion of the liner when heated by the internal combustion within the motor, of a light weight metallic alloy piston arranged to reciprocate in the liner, the said liner being made of metal having a coefficient 25 of thermal expansion approximately the same as those of the cylinder casting and piston metals.
6. In an internal combustion motor, the combination with a composite cylinder comprising a light weight metallic alloy casting with a cylindrical wall surrounded by cooling means, and a cylindrical liner secured 30 concentrically within the said cylindrical wall, the liner having its outside diameter less than the diameter of the inner wall of the casting to afford a clearance between the 35
- liner and casting adapted to be taken up by the expansion of the liner when heated by the internal combustion within the motor, and part of one of the adjacent surfaces of the cylinder wall and liner being recessed to form heat insulating space between said adjacent surfaces, of a light weight metallic alloy piston arranged to reciprocate in the liner, the said liner being made of metal 40 having a coefficient of thermal expansion approximately the same as those of the cylinder casting and piston metals.
7. In an internal combustion motor, the combination with a composite cylinder comprising a main cylindrical wall formed of metal having, in comparison with iron, a low specific gravity and a high coefficient of thermal conductivity, cooling means on the outer side of said cylindrical wall, and a 45 metallic liner secured concentrically within the said cylindrical wall and having its outside diameter less than the inner diameter of the cylindrical wall to afford a clearance adapted to be taken up by the expansion of 50 the liner when heated by the internal combustion within the motor, of a piston arranged to reciprocate in the liner and formed of metal having a low specific gravity in comparison with iron, the said liner having 55 a coefficient of expansion approximately the same as that of the piston and a high coefficient of thermal conductivity in comparison with iron.
- In testimony whereof I hereunto affix my 60 signature.

ZAY JEFFRIES.
